UNITED STATES PATENT OFFICE.

CASPAR SCHOCH, OF TRUCKEE, CALIFORNIA.

SAW-MILL CARRIAGE.

SPECIFICATION forming part of Letters Patent No. 274,227, dated March 20, 1883.

Application filed January 2, 1883. (No model.)

To all whom it may concern:

Be it known that I, CASPAR SCHOCH, of Truckee, county of Placer, State of California, have invented an Improved Reciprocating Carriage and Automatic Block-Set for Saw-Mills; and I hereby declare the following to be a full, clear, and exact description thereof.

My invention relates to new and useful improvements in traveling carriages and automatic block-sets for saw-mills.

The improvements consist generally in a novel means for reciprocating the carriage and regulating at pleasure the length of its travel, and in a novel means for setting over after each cut the block or timber for a new cut.

More specifically, my invention consists in a double rack upon the carriage, an adjustable spur-gear adapted alternately to engage either directly or indirectly with each of said racks to advance or return them, a trip-lever to which said spur-gear is attached, and suitable catches engaging therewith, and stops to trip the catches, whereby at the end of each stroke the trip-lever is vibrated to throw its spur-gear in and out of engagement with the racks; further, in a pawl-and-ratchet mechanism operated by a swinging arm engaged indirectly by a weighted lever and moved by its fall when released at the end of the return-stroke of the carriage, whereby the block or timber-holder is set over for a new cut; further, in the adjustability of certain of the catches and stops, whereby the stroke of the carriage may be lengthened or shortened, all of which will hereinafter fully appear.

My object in this invention is to provide a ready and effective means for automatically reciprocating the carriage and setting over the block, and to dispense with the weight which is ordinarily used to return the carriage.

Referring to the accompanying drawings, Figure 1 is a perspective view of my device, showing carriage B advancing. Fig. 2 is a detail of Fig. 1, showing the spur-gear d in engagement with rack b. Fig. 3 is an elevation of my device, showing carriage B at the limit of its return, the pointed lever C being depressed and the gear d being in engagement with pinion e'. Fig. 4 is a detail showing jointed lever C, its points of pivot, its forward catch, and driving-shaft D.

A may represent the foundation; B, the car-

riage adapted to travel thereon. Under the edge of the carriage is a rack, b, while another, b', is formed upon the outside.

C is a long jointed lever, pivoted in two places, at c and c², Fig. 4. This lever is shown clearly in Fig. 4, its joint being at c', and formed by the loose insertion of a tongue on one part into a socket upon the other.

D represents the driving-shaft, not journaled in the foundation, but in the jointed trip-lever C, as shown in Fig. 4. This shaft carries a spur-gear, d, adapted to engage directly with the rack b above it, as shown in Fig. 2.

E is a short shaft secured in the foundation, upon which is mounted a gear-wheel, e, having an inner flange or collar shaped into a small pinion, e', Figs. 2 and 3. The gear e meshes with the outer rack, b', while the pinion e' is in line with and is adapted, as I shall show, to be engaged by the spur-gear d when the latter is thrown out of engagement with its rack b, Fig. 3. This movement of the spur-gear d is caused by the alternate elevation and depression of the joint of the trip-lever, operated from each end as follows: Near one end of the foundation is a pivoted notched catch, F, held to its place by spring f. Near the other end is another such catch, G, held to its place by a spring, g. One end of the trip-lever C is adapted to engage with and be held down by the catch F, and the other end to be supported by the catch G, according as each end is raised or lowered.

H is a double-armed spring, one arm of which is attached under the end of the lever C. The other passes up under the carriage B, and is adapted to be moved back and forth to influence the other arm by means of an inclined plane, a², and a pin, a, under said carriage, Fig. 3. Another pin, a', near the other end of the carriage is adapted to come in contact with catch F, Fig. 3.

The operation of these devices is as follows: Suppose the carriage to be in the position shown in Fig. 1, in which the long arm of the lever C is depressed and held down by the engagement of the short arm with the catch F. In this position the joint of the lever is thrown up, and its spur-gear d is in direct engagement with the rack b. This engagement is further shown in Fig. 2. The revolution of shaft D causes the progression of the carriage in

the direction of the arrow, Fig. 2, until the pin a' comes in contact with and forces back catch F . This releases that end of the lever C and allows the spring H (its upper arm being depressed by inclined plane a^2) to throw up its other end into engagement with catch G . This depresses the joint of lever C , throwing its spur-gear d out of engagement with rack b and into engagement with pinion e' , when, by the continued revolution of shaft D in the same direction, power is transmitted through pinion e' and gear to the rack b' , and the carriage immediately enters upon its return movement in the direction of the arrow, Fig. 3. The position to which the parts are thrown to effect the return is seen in Fig. 3, in which the carriage has completed the return. As it recedes the pin a comes in contact with the upper arm of spring H , Fig. 3, and, forcing it back, causes its other arm to pull down upon lever C . When the end of the carriage reaches the catch G it forces it back, releasing the lever C , when the spring H pulls its end down, throwing down its other end into engagement with catch F and elevating its joint to throw its spur-gear out of engagement with pinion e' and into engagement with rack b , when the carriage again progresses. This is all accomplished by the revolution of the driving-shaft D in one direction. The play of the joint is not great, and the end of shaft D being journaled near the joint, it may have sufficient play to move up and down slightly. The carriage B is the means for carrying forward to the saw, the timber to be cut. After one cut is made it is obvious that some adjustment is necessary to set the timber over in line of the saw again. This adjustment is of importance, especially in shingle-mills, where my invention is particularly applicable. Here is required an accurate and quick automatic adjustment. The means I have devised are as follows:

At the rear end of the carriage is a standard, I , to the top of which is pivoted a swinging-arm, J , Fig. 1.

K is a horizontal shaft mounted on the carriage, and carrying a number of toothed wheels, k . Upon the same shaft is a ratchet, L , with which a pawl, l , extending from the swinging-arm J , engages. By moving this arm the pawl will feed the ratchet and turn the toothed wheels k .

I have not deemed it necessary in this connection to illustrate the holding mechanism for the block, as such devices and their connections are well known. It is sufficient here to say that in a suitable manner the shingle-block is held and rested upon the toothed wheels k , and by their movement, as described, the said block is set over in line with the saw. A spring, l' , returns arm J to its place.

M is a toggle-lever, one end of which is secured to the carriage, the other end by a rod, m , to the lower end of arm J . A rod, N , is secured to the joint of the toggle-lever M , and hangs down past the end of the carriage, and

has a hook, n , on its end. If the rod N be pulled down, it depresses the joint of toggle-lever M , forces its loose end out, and through connecting-rod m moves out arm J to feed the ratchet.

O is a slotted plate, secured to the foundation and adapted to be adjusted forward or back thereon the length of its slots.

Pivoted to the end of plate O is a lever, P , with a weight, p . A hooked arm, Q , extends upward from this lever, and is adapted, when the lever is raised, to receive under it the end of the rod N .

R is a notched catch, weighted and pivoted to the plate O . Its top is adapted to be engaged by a pin, r , on the carriage. A pin, p' , on lever P engages with said notched catch, and supports said lever when raised, Fig. 3.

S is an elbow-lever pivoted to the plate O . One arm extends under the end of lever P , the other up beside the carriage B , behind a pin, s , projecting from said carriage, Fig. 1. When the carriage is in the position shown in Fig. 1 the pin s is pressing forward the upper arm of lever S . As it progresses it gradually raises its lower arm under the end of lever P , which said lever is thus raised until its pin p' engages with the catch R , when it is supported in such position that its hooked arm Q is raised high enough to receive under it the rod N , Fig. 3. The carriage then returns, and before it reaches its limit the end of rod N passes under the upper end of arm Q , and immediately the pin r forces back catch R , releases weighted lever P , which falls, pulling down arm Q . This depression of arm Q draws down rod N to operate the pawl-and-ratchet feed, as heretofore described.

It may be desirable at times to shorten or otherwise regulate the travel of the carriage. To do this I remove pin a and set it farther back in the carriage, as shown by dotted pin w , so that it may engage the arm of spring H at an earlier moment, Fig. 1. Then I extend a stop (here shown by an adjustable rod, x , also dotted in) farther back from the rear end of the carriage, so that it may force back the catch G earlier, Fig. 1; and to make the setting-over device correspond I adjust the slotted plate O farther forward to meet the shortened travel of the carriage.

Having thus described my invention, what I claim as new, and desire to secure by Letters Patent, is—

1. In a saw-mill, means for reciprocating the traveling carriage, consisting in a double rack upon the carriage, an adjustable spur-gear adapted to alternately engage directly or indirectly with each of said racks to advance or return them, a trip-lever to which said spur-gear is attached, and suitable catches engaging therewith, and stops to trip the carriage, whereby at the end of each stroke the trip-lever is vibrated to throw its spur-gear in and out of engagement with the racks, substantially as herein described.

2. In a saw-mill, a traveling carriage having

racks $b b'$, in combination with the jointed pivoted trip-lever C, carrying a spur-gear, d, at its joint, the gear e, and pinion e', all arranged as shown, and springs operated by the traveling carriage to alternately depress and elevate each end of the lever, catches to engage therewith, and stops to trip said lever, substantially as and for the purpose herein described.

3. In a saw-mill, a traveling carriage having racks $b b'$, in combination with the jointed pivoted trip-lever C, carrying a spur-gear, d, and driving-shaft D, at its joint, and having an actuating-spring, H, operated by devices on the traveling carriage to alternately elevate and depress each end of the trip-lever, the gear e, and pinion e', the notched spring-catches F G, engaging with the ends of the lever and forced back by contact with the traveling carriage to release said lever, substantially as and for the purpose herein described.

4. In a saw-mill, a traveling carriage having racks $b b'$, pins $a a'$, and incline a^2 , in combination with the jointed pivoted trip-lever C, carrying a spur-gear, d, and having an actuating-spring, H, arranged as shown, the gear e, pinion e', and notched spring-catches F G, all arranged and operating substantially as and for the purpose herein described.

5. In a saw-mill, the reciprocating carriage

B, horizontal shaft K, having toothed wheels $30 k$, and the feed-ratchet L, in combination with the pivoted sprung-arm J, connecting-rod m, toggle-lever m'' , and hanging rod N, and a means operated by the traveling carriage for depressing said rod and feeding the ratchet, substantially as and for the purpose herein described.

6. In a saw-mill, the reciprocating carriage B, horizontal shaft K, having toothed wheels k , and feed-ratchet L, in combination with the pivoted sprung-arm J, pawl l, toggle-lever M, connecting rod m, and hanging rod N, with hooked end, and the means for automatically depressing said rod N and feeding the ratchet, consisting of the weighted lever P, having pin p' , hooked arm Q, elbow-lever S, operated by a pin on the traveling carriage to raise the lever P, and catch R, adapted to engage with pin p' and support lever P, and to be disengaged by a pin on the said carriage, all arranged and operating substantially as and for the purpose herein described.

In witness whereof I hereunto set my hand.
